UNITED STATES PATENT OFFICE.

CECIL H. SMITH, OF THE UNITED STATES NAVY.

SPARK-PLUG.

1,007,806.

Specification of Letters Patent.

Patented Nov. 7, 1911.

Application filed July 1, 1909, Serial No. 505,361. Renewed April 15, 1911. Serial No. 621,305.

To all whom it may concern:

Be it known that I, CECIL H. SMITH, a citizen of the United States, residing temporarily at Brooklyn Navy Yard, New York, U. S. S. *Connecticut*, have invented certain new and useful Improvements in Spark-Plugs, of which the following is a specification.

This invention relates to spark plugs for gas engines, and has for its object to provide a detachable spark terminal for the engine ground.

A further important object is to provide a spark terminal which is adapted for engagement with various plugs when the usual engine ground terminal is broken.

In the drawing forming a part of the specification, Figure 1 is a side elevation of my improved spark plug. Fig. 2 is a vertical longitudinal section thereof. Fig. 3 is a horizontal section taken on the line 3-3 of Fig. 2. Fig. 4 is a detail view of the insulating core.

Referring to the drawing 1 indicates the casing or body member which may be of any desired cross sectional form, and has its lower end contracted in diameter as shown at 2 and exteriorly screw threaded for engagement in the engine casing. Centrally positioned within this casing is the insulating core 3 which may be formed of mica or other suitable insulating material. This core is enlarged adjacent to its lower end as shown at 4, and is adapted to be seated upon the shoulder 2' formed in the casing 1 by the lower contracted portion 2 thereof.

A cap 5 is disposed upon the upper end of the body member 1, and is formed with a depending sleeve 6 which extends into the body member, and through which the core 3 is adapted to extend. The end of the sleeve 6 is engaged upon the upper surface of the enlargement 4 of the core, and is adapted to hold the same against any vertical movement therein. To secure the cap 5 and sleeve 6 within the body 1, a pin 7 is extended through an opening 8 formed in the casing, and is provided with a groove 8' adjacent to its outer end, to receive the upper bifurcated end of a leaf spring 9, which is secured to the exterior of the casing 1. This spring normally tends to force the shank of the pin 8 inwardly into a recess 10, formed in the periphery of the sleeve 6. In this manner any movement whatsoever of the sleeve and core will be absolutely prevented.

A conducting rod 11 extends centrally through the insulating core 3, and has a nut 12 threaded upon its upper end. The circuit wire is adapted to be secured to the rod 11 and held in engagement therewith between the nut 12 and the upper end of the core. The rod 11 is preferably formed of steel and extends entirely through the core. A terminal point member 13 is attached to the lower end of the core 3, and has its extremity spaced from the end of the rod 11. The point 13 has its upper portion coiled to resiliently clasp the core, and is of sufficient resiliency to retain the point in position against all liability of accidental displacement. Adjacent the coiled portion, the terminal member 13 is provided with an outwardly bowed portion adapted to bear against the inner surface of the casing 1 to ground the current in the engine through the casing, as is usual in this type of plug. Thus the sparking point may be readily disengaged from the core when desired and replaced by a new one, thereby maintaining a high degree of efficiency of the spark plug.

In operation, the sparking point is first secured to the lower end of the core as above described, and the sleeve and cap are placed upon the same and bear upon the enlarged portion 4 thereof. The electric circuit wire is now attached to the upper extremity of the conducting rod 11, and the nut 12 adjusted to securely retain the wire in position. The lower portion of the core 3 and consequently the sparking point 13 is now placed in the lower contracted extension 2 of the body member 1, the base of the enlargement 4 bearing upon the shoulder 2' thereof. When the parts are in this position the opening 8 in the casing 1 and the recess 10 in the sleeve 6 will register. It will be obvious of course, that before the sleeve can be positioned within the body member 1, the pin 7 must be drawn outwardly into the opening 8. After the core has been properly placed within the body of the plug, the pin 7 is released, whereupon the spring 9 will force the pin inwardly into the recess 10 and securely lock the various parts in their operative position. By this construction, the plug may be disassembled without the necessity of employing a wrench, and new sparking points may be secured to the insulating core at a trifling cost, thus practically producing an entirely new plug.

From the foregoing it will be seen that I

have provided a spark plug which is of extremely simple construction, the various parts being held in their operative position against any possibility of accidental derangement. In view of the quick adjustment of the various parts it will be seen that but a few minutes would be required to replace the old sparking point by a new one.

10 My improved spark plug may be very inexpensively manufactured, is highly efficient in operation, and extremely durable in use.

What is claimed is:

15 In a spark plug, the combination with a body member adapted to be secured in a hydro-carbon engine, an insulating core positioned therein having a portion spaced peripherally from the body member, a conducting member engaged through the core

and a spark terminal detachably engaged 20 around the core and bearing against the body member, said terminal member comprising a portion of wire of proper material having a helix at one end adapted for circumscribing engagement with the core, 25 and a terminal extension adapted to extend longitudinally of the plug and having an inwardly turned portion disposed in juxtaposition with the conducting member, said longitudinally extending portion having an 30 outwardly bowed portion bearing against the body member, for the purpose described.

In testimony whereof I affix my signature, in presence of two witnesses.

CECIL H. SMITH.
